DENTAL CUSPIDOR CONSTRUCTION

Edward L. Monnot, Canton, Ohio, assignor to
 The Weber Dental Manufacturing Company,
 Canton, Ohio, a corporation of Ohio

Application July 23, 1937, Serial No. 155,235

4 Claims. (Cl. 4—263)

The invention relates generally to dental apparatus including a fountain cuspidor and a water supply unit supported on a suitable stand or pedestal enclosing water supply and discharge connections.

More particularly, the invention relates to dental apparatus in which a dental cuspidor is adapted to swing with respect to the stand and the water supply and valve assembly supported thereby.

10 In prior constructions having a cuspidor and water supply unit including a valve head for controlling the water supply to the various parts, the whole assembly has been mounted for swinging on the supporting stand or pedestal.

15 In such constructions, when the assembly is swung to change the position of the cuspidor, the valves requiring manipulation by the dentist are usually in a difficult or awkward position to be reached by the dentist, and the drinking water supply nozzle supported on the unit is

20 also likely to be in an inconvenient location. This is particularly true if the dentist is absorbed in working on the patient's teeth when reaching for the valves or the water glass.

25 Moreover, where the whole cuspidor, water supply and valve assembly is swung relative to the supporting stand, a swivel joint is required in the water line connection to the water supply unit, and this joint is always under line pressure when water is being supplied to the water supply unit to be used for flushing the cuspidor or for supplying drinking water, tending to cause leakage at said swivel joint.

30 In such prior constructions, a saliva ejector has been provided for being operated by water from the water supply unit and discharging into the cuspidor. Thus, the water supply unit is

35 under line pressure tending to cause leakage at said swivel joint if the saliva ejector is being used, although water may not be required for merely flushing the cuspidor or for supplying drinking water.

40 It is therefore an object of the present invention to provide a cuspidor and water supply unit in which the cuspidor can swing while the water supply unit and valve assembly remains stationary.

45 Another object is to provide a swinging cuspidor construction which has no swivel joints subjected to full water line pressure at any time.

50 Another object is to provide a swinging cuspidor construction in which the water valves for the cuspidor and the other attachments requiring water are always located in the same position

relative to the supporting stand or pedestal, and to the position of the operator.

A further object is to provide a swinging cuspidor and water supply unit having a saliva ejector which does not discharge into said cuspidor. 5

A still further object is to provide a cuspidor and water supply unit which is simple and compact in construction and convenient and efficient in use.

These and other objects are attained by the 10 parts, improvements, arrangements, combinations and sub-combinations constituting the dental apparatus which comprises the present invention, the nature of which is set forth in the following general statement, and preferred embodiments 15 of which together with their mode of use are disclosed and described in the following description, and which are particularly and distinctly set forth in the appended claims forming part hereof.

The nature of the improved dental cuspidor 20 construction of the present invention may be set forth in general terms as including a supporting stand or pedestal on which is mounted a bracket arm carrying a valve head and water supply unit having an independent drain, a cuspidor being mounted for swinging with respect to the bracket arm supporting said valve head and water supply unit, means externally of the arm providing a swivel water line connection between the valve head and cuspidor, the swivel means having its 25 swivel axis laterally offset from the water supply unit and being outside of the cuspidor, and saliva ejector means on the valve head adapted for discharging into said independent valve head drain.

Further improved details of construction and 30 arrangement are hereinafter set forth.

By way of example, an embodiment of the improved dental apparatus comprising the present invention is illustrated in the form of dental cuspidor construction in the accompanying drawings forming part hereof, in which— 35

Figure 1 is a perspective view of one embodiment of the present invention, showing the swinging cuspidor and water supply unit mounted on a suitable pedestal; 40

Fig. 2 is an enlarged fragmentary vertical section thereof, partly in elevation;

Fig. 3 is a further enlarged fragmentary vertical section of the valve head and water connections shown in elevation in Fig. 2; 45

Fig. 4 is a fragmentary section as on line 4—4 Fig. 3;

Fig. 5 is a fragmentary side elevation, partly in section, of the parts shown in Fig. 2; and 50

55

Fig. 6 is an enlarged fragmentary section of the valve head as shown in elevation in Fig. 5.

The same numerals refer to the same parts throughout the several views of the drawings.

5 While I have shown the improved swinging cupidor and water supply unit mounted on a pedestal, the same may be mounted on other supporting means, as for example, on a bracket arm extending from a dental instrument stand. 10 As shown in the drawings, the upper part of the hollow supporting pedestal 7 is reduced at 8 to form an annular shoulder 9, and the tubular upright arm 10 for supporting the water supply unit has an offset portion 11 provided with a depending annular flange 12, which telescopes over the reduced portion 8 and is supported by said shoulder 9. 15

Preferably, the flange 12 is secured to the reduced portion 8 of the pedestal by a screw 13 for preventing rotation of the arm on the pedestal. 20

The upper end of the offset portion 11 is preferably tubular for receiving and swiveling the reduced depending sleeve portion 14 of the tubular cupidor bracket arm 15, which supports the cupidor bowl 16 on its outer end. The hollow arms 10 and 15 act as discharge conduits for conducting liquids into the offset portion 11. 25

The sleeve portion 14 has formed thereon an annular shoulder 17 which is rotatably supported on the upper end of the offset portion 11, and a bearing washer 18 may be provided between the shoulder 17 and the offset portion 11 as shown. Preferably, the sleeve portion 14 is provided with spaced annular grooves, the lower groove having bearing rings 19 therein, and the upper groove 20 slidably receiving the shank of a retaining screw 21, for permitting limited swinging movement while preventing upward movement of the bracket arm 15 with respect to the offset portion 11. 30

The outer end of the cupidor bracket arm 15 has an upwardly open socket portion 22 which is adapted to receive the neck 16' of the cupidor bowl 16. Preferably, the bottom of neck 16' rests upon a rubber gasket 23 which is supported by the annular flange 24 of the socket. Another rubber gasket 25 encircles the neck 22 above the gasket 23, and a jam nut 26 and washer 27 are provided for compressing gasket 25 between the socket wall and the neck 22 for holding the cupidor in position without crushing said cupidor neck. 35

A strainer 28 may be provided in the neck 16' through which liquids from the bowl 16 pass and drain downwardly through arm 15 into the offset portion 11. A drain pipe 29 is provided in pedestal 7 and communicates at its upper end 30 with the interior of offset portion 11, so that liquids may drain from the bowl 16 or from the tubular arm 10 into and through the drain pipe 29, which conducts them to a suitable outside drain or sewer connection. 40

The upright arm 10 is reduced at its upper end to form a socket 32 carrying a receptacle 33 for supporting a water glass 34. The receptacle 33 has a central drain opening 35 communicating with the upper end of a drain pipe 37 in the arm 10. 45

The arm 10 is enlarged adjacent its reduced upper end to form a housing 38 for a valve head 39 and for the drain pipe 37 which discharges into the arm 10 below the housing 38. The valve head 39 or water supply unit is mounted on the housing wall 38 by bolts 38a, and a tubular pro-

jection 40 extends rearwardly from the bottom end of the valve head 39 through the housing wall. A water pipe 41 is connected at its upper end to said projection 40 for communicating therewith by suitable coupling means indicated 5 at 42.

As shown in Fig. 2, the lower end of pipe 42 is preferably secured to an elbow fitting 43 having a strainer 44 and cleanout plug 45. The fitting 43 is connected by coupling means 46 to a connector tube 47 secured in the tubular wall of the pedestal 7, and a main water supply pipe 48 in the pedestal is connected to said connector tube 47. Thus, water from the supply line 48 flows through the pipe 41 into tubular projection 40 15 of the valve head.

The bore 50 of projection 40 communicates with a preferable vertical passage 51 formed in the valve head 39, and vertically spaced lateral passages 52, 53 and 54 lead from passage 51 to 20 valve chambers 55, 56 and 57 respectively. Valves 58, 59 and 60, connected to the valve head 39, are provided with valve plungers 61, 62 and 63 respectively, for abutting the ends of lateral passages 52, 53 and 54 for controlling the flow of 25 water into chambers 55, 56 and 57 respectively.

The valve chamber 55 communicates preferably through ports 64 with the passage 65 of a discharge tube 66 (Fig. 4) for supplying water to a saliva ejector connection indicated generally 30 at 67.

The valve chamber 56 communicates through ports 68 with the passage 69 of a discharge tube 70 leading to a swivel connection indicated generally at 71 externally of the arms 10 and 15 35 for supplying water to the bowl 16 for flushing purposes. The swivel connection is preferably coaxial with the offset portion 11 on which the cupidor arm is swiveled, as indicated by the dot-dash line in Figs. 2 and 3, so that the cupidor arm 15 and the water supply pipe to the bowl 16 40 swivel about the same axis.

The valve chamber 57 communicates through ports 72 with the passage 73 of a discharge tube 74 communicating with a pipe 75 for supplying 45 water to the glass 34.

Thus the valves for controlling the flow of water to the various parts of the apparatus are located close together in a conveniently accessible place, and always remain in that location regardless of where the cupidor is swung, since the valve head is stationary with respect to the pedestal. 50

The saliva ejector connection 67 preferably includes a conduit 76 having a relatively small bore 77 at its inlet end and an enlarged bore 78 at its discharge end. A side aperture 79 is provided into the bore 78 at its junction with bore 77, and a sleeve member 80 forms an annular chamber 81 around the conduit 76 communicating with said aperture 79. A flexible tube 82 is connected at one end to said sleeve member 80 and communicates with said chamber 81 and the other end of said tube 82 is equipped with the usual terminal 83 for insertion into a patient's mouth. 55

When valve 58 is open, as shown in Fig. 6, water flows through ports 64 and passage 65 through bore 77, and the increased velocity of the water flowing from bore 77 into bore 78 causes a suction in the flexible tube 82. This suction is utilized in the usual manner for removing blood, pus and the like from the patient's mouth through terminal 83, and draws it into the bore 78, from which it is discharged together with 70 75

the water stream out through the goose neck pipe 85 and into tubular arm 10 to drain out through pipe 29 in the pedestal. Since the discharge pipe 85 is not connected with the bowl 16, no swivel connection therebetween is required, thereby lessening the tendency for leakage at such a connection. Moreover, the patient is spared the sight of blood and pus in the cuspidor bowl 16, which tends to cause nausea.

10 The swivel connection 71 connects tube 70 with the pipe 86 for conducting water into the cuspidor bowl 16 for flushing the same, and the swivel connection preferably includes a pipe nipple 87 coupled to tube 70 at one end and screwed into a packing sleeve 88 in which a vertical journal member 89 is swiveled. The journal member 89 is provided with a bore 90 and has lateral ports 91 providing communication between the upper end of the bore and an exterior groove 92 in the journal member, which groove communicates with the bore of the pipe 87.

15 The pipe 86 is secured at one end in the lower shouldered end of journal member 89 and communicates with the lower end of the bore 90.

20 The other end portion of pipe 86 extends through a rubber washer 93 in the side wall of the cuspidor bowl 16, and the end of the pipe is bent downwardly as shown in Fig. 2 for discharging water into the bottom portion of the bowl.

25 Suitable packings 94 are provided around the journal member 89 within the ends of sleeve 77, and a packing nut 95 is screwed on the member 89 for compressing the packings against the ends of sleeve 88.

30 By means of the present improved construction wherein the cuspidor bowl swings and the water supply unit remains stationary, the valve head 39 can always be under line pressure from the water supply without the occurrence of any leakage, because the single water line swivel connection 71 is subjected to water pressure only when valve 59 is open to supply water to the bowl 16. When this occurs, however, the water from pipe 86 runs freely into the bowl, so that the 35 amount of pressure at the swivel connection 71 is wholly insufficient to cause any leakage at the swivel connection.

35 The valves 58, 59 and 60 are operable to supply water to the saliva ejector, cuspidor bowl and water glass, either selectively or all at the same time, and in any case the liquid discharged from the saliva ejector and the water glass receptacle drains into the upright arm 10 and thence into the pedestal drain pipe 29, independently of the 40 cuspidor drain.

45 The present improved apparatus provides a cuspidor and water supply unit which is simple, compact and inexpensive in construction, and convenient and efficient in use.

50 Various modifications in the details of construction and arrangement may be made without departing from the scope of the invention defined in the appended claims.

I claim:

55 1. Dental apparatus including a pedestal having a drain pipe therein, a tubular upright arm rigidly mounted on said pedestal and communicating with said drain pipe, a cuspidor swiveled on said upright arm for communicating with said drain pipe, a valve head mounted on said upright arm, saliva ejector means connected to said valve

head and discharging into said upright arm, and means externally of the arm providing a swivel connection with the valve head for discharging water into the cuspidor, the swivel means having its swivel axis laterally offset from the valve 5 head and being outside of the cuspidor.

2. Dental apparatus including a pedestal having a drain pipe therein, a tubular upright arm having a laterally offset portion secured on said pedestal, said upright arm providing a discharge 10 conduit communicating with said drain pipe, a tubular cuspidor arm swiveled on said offset portion and providing a discharge conduit communicating with said drain pipe, a cuspidor mounted on said cuspidor arm, a valve head 15 mounted on said upright arm, saliva ejector means connected to said valve head and discharging into said upright arm, and means externally of the arms providing a swivel connection with said valve head for discharging water into said cuspidor, the swivel means having its swivel axis laterally offset from the valve head and being outside of the cuspidor.

25 3. Dental apparatus including a pedestal having water supply and discharge connections therein, a tubular arm non-rotatably mounted on said pedestal and communicating with said pedestal discharge connection, a tubular cuspidor arm swiveled on said non-rotatable arm and communicating with said pedestal discharge connection, 30 a cuspidor mounted on said cuspidor arm, a valve head mounted on said non-rotatable arm, means connecting said valve head to said pedestal water supply connection, a water glass receptacle on the end of said non-rotatable arm having a drain 35 discharging into said arm, means connected to said valve head for supplying water to said receptacle, means externally of the arms providing a swivel water conduit connection between the valve head and the cuspidor, the swivel water conduit 40 connection means having the swivel axis laterally offset from the valve head and being outside of the cuspidor, and saliva ejector means connected to said valve head and discharging into said non-rotatable arm.

45 4. Dental apparatus including a pedestal having water supply and discharge connections therein, a tubular upright arm having a laterally offset portion non-rotatably mounted on said pedestal, said arm communicating with said pedestal discharge connection, a tubular cuspidor arm swiveled on said offset portion and communicating with said pedestal discharge connection, a cuspidor mounted on said cuspidor arm for draining thereinto, a valve head mounted on said upright arm, means connecting said valve head to said pedestal water supply connection, a water glass receptacle on said upright arm, means connected to said valve head for supplying water to said receptacle, means providing a drain connection from the receptacle into said upright arm, a swivel connection externally of the arms for conducting water from said valve head to said cuspidor, the swivel connection having its swivel axis laterally offset from the valve head and being outside of the cuspidor, a saliva ejector operatively connected to said valve head, and a discharge pipe for said saliva ejector discharging into said upright arm.
